UNITED STATES PATENT OFFICE.

FERNAND E. D'HUMY, OF ENGLEWOOD, NEW JERSEY, ASSIGNOR TO RAMP BUILDINGS CORPORATION, OF NEW YORK, N. Y., A CORPORATION OF DELAWARE.

GARAGE.

Application filed September 15, 1925. Serial No. 56,483.

This invention relates to buildings, and more particularly to storage buildings, such as garages, wherein the several floors are connected by inclined driveways. The objects of the invention are to improve the construction of buildings of this character and to facilitate the safe and rapid travel of vehicles from floor to floor.

In the drawings, Fig. 1 is a horizontal section through a building, on the line 1—1 of Fig. 2, illustrating one embodiment of my invention;

Fig. 2 a vertical section on the line 2—2 of Fig. 1;

Fig. 3 a vertical section on the line 3—3 of Fig. 2;

Fig. 4 a sectional perspective view of a portion of my improved building; and

Fig. 5 a horizontal section through a building, showing a slightly modified form of my invention.

Referring to the structure shown in Figs. 1 to 4 inclusive, 1 designates the end walls and 2 the side walls of the building. The end walls are provided with suitable windows 3, and one of said walls is formed with a doorway 4 leading to the ground floor 5 of the building. Extending in a vertical plane across the center of the building, intermediate the side walls 2 and parallel to them, is an open floor-supporting structure dividing the plan of the building into two sections. This structure comprises a row of columns 6 and horizontal floor-supporting girders 7 connecting them. Located at one side of the dividing structure is a group of superposed floors 8, and located at the opposite side of said structure is a group of superposed floors 9. The floors in one group are disposed in horizontal planes intermediate the planes of the floors of the other group, and the floors in both groups extend from the dividing structure to the side walls 2. The inner edges of the floors 8 and 9 are supported by the open dividing structure 6—7, and intermediate said structure and the side walls 2 said floors are supported by columns 10. There are two rows of these columns 10 for each of the floor groups and they are arranged at opposite sides of central passageways 11 upon the floors 8, and at opposite sides of a central passageway 12 upon the floors 9. The passageways 11 and 12 extend parallel to the intermediate dividing structure. The

columns 10 in each row are suitably spaced apart to provide parking spaces for automobiles therebetween at opposite sides of the passage-ways. These parking spaces extend in rows along opposite sides of the dividing structure and along the side walls 2. The inner edges of the floors 8 and 9 preferably overlap at the dividing structure, as shown in Fig. 3, to slightly increase the storage space and provide clearance for the front ends of the automobiles parked in the inner rows of storage spaces.

Two series of superposed, oppositely inclined ramps 13 and 14 are located at opposite ends of the building and extend transversely past the ends of the dividing structure to points spaced substantially equal distances from opposite sides of said structure. Each ramp of each series connects two floors located at opposite sides of the dividing structure and leads to the passage-ways 11 and 12.

The ramps, as shown in Figs. 1 to 4, are supported along their outer longitudinal edges by the end wall structures of the building, and at their inner longitudinal edges are supported by the columns 10 at the end of the two inner rows of columns and by the end columns 6 of the dividing structure. The columns 10 and 6 are preferably connected by girders which extend along and support the inner longitudinal edges of the ramps. The inner longitudinal edges of the ramps are thus supported by an open structure and the passage-ways over the ramps are exposed through said structure to the spaces between the floors 8 and the spaces between the floors 9. The ramps 13 and 14 are outwardly banked or inclined, as shown in Fig. 2. The ramps merge with passage-ways 11 and 12 along diagonal lines 15 so that the wheels of the turning automobile will reach the inclination of the ramp simultaneously. This ensures that the automobile will travel smoothly from the floors to the ramps and from the ramps to the floors without danger of its frame being twisted as the turns are made.

The construction and arrangement of the floors, the ramps and the supporting structures, just described, greatly facilitate the safe and rapid travel of vehicles through the building from floor to floor. The spaces between the floors and the spaces between the ramps are inwardly exposed to each other

through their open supporting structures, so that a driver, at any point in the path through the building, may look across the building and observe the traffic upon the next adjacent floors above and below him and also upon the ramps leading to said floors. He may then properly regulate the speed of his car and direct it to avoid collision with cars approaching rapidly from the opposite direction. This observation across the building to different levels is made possible by the combination of the staggered floor levels, the transverse arrangement of the ramps, and the open supporting structures. The particular arrangement of the ramps with relation to the open dividing structure 6-7 contributes greatly to this visibility feature. By reason of the fact that the dividing structure is medially disposed with respect to the length of the ramps, it is possible for a driver just entering upon a ramp 13 to look from a position A clear across the building, through the open structures, and observe a descending car at the point B upon the ramp 14 at the opposite end of the building. From a point of observation such as C in passage 11 the next adjacent floors above and below C and the ramps leading to said floors may be observed. A driver moving in either direction from C can therefore see for a long distance ahead and observe if there are other cars in his path or if any cars are being backed from the storage spaces into the passage-ways.

35 The open structure of the building throughout its area and height, in addition to the advantages pointed out, also provides for the rapid dissipation of the exhaust gases from the automobiles. The open structure furthermore permits the light from the windows 3 to penetrate clear across all of the floors. The windows are so located as to admit light directly to the ramp passageways and add to the visibility at these points.

45 The building shown in Fig. 5 is similar to that just described, with the exception that the open dividing structure 6-7 extends entirely across the building and the ramps 13 and 14 are spaced inwardly from the end walls and extend through the dividing structure. The opposite ends of the ramps are supported between two pairs of the columns 10 located at opposite sides of the dividing structure, and intermediate their ends the ramps are supported between a pair of the columns 6 of the dividing structure. The ramps, their supporting girders and the floors 8 and 9 are all tied to the columns 6 and 10 of the two floor groups at opposite sides of the ramps, and mutually support each other. Each floor is connected to the columns of the dividing structure and to two adjacent floors of the opposite group of floors, by two oppositely inclined structures which form driving ramps. This provides a very strong building structure at the points where the ramps are located.

What I claim is:

A garage building comprising two groups of superposed horizontal storage floors located at opposite sides of a vertical dividing plane, the floors of one group being disposed in planes intermediate the planes of the floors of the other group; and two series of oppositely inclined superposed ramps extending through the dividing plane at spaced points and extending out at opposite sides of the plane, each ramp of each series connecting two storage floors located at opposite sides of the dividing plane the inner side edges of said ramps being open, the spaces between the floors of each group being open to the opposed spaces of the other group through and along the length of the dividing plane extending between the two series of ramps to render any two adjacent superposed storage floors of either group visible from the opposed intermediate floor of the other group at any point of observation along the space between the ramp connections of said intermediate floor, the passageways over the ramps of both series being laterally open to the adjacent floors of both groups over the inner longitudinal edges of the ramps, whereby from a position on any one of said floors or on any one of said ramps the floors and ramps at adjacent levels will be visible and whereby from any floor the entire lengths of the ramp passageways leading thereto will be visible across the inner longitudinal edges of the ramps and through the dividing plane.

In testimony whereof I hereunto affix my signature.

FERNAND E. D'HUMY.
